(57) **CLAIM**

The ornamental design for the nasal cannula body, as shown and described.

DESCRIPTION

FIG. 1 is a perspective view of a nasal cannula body showing our design.

FIG. 2 is a front view thereof.

FIG. 3 is a rear view thereof.

FIG. 4 is a left side view thereof.

FIG. 5 is a right side view thereof.

FIG. 6 is a top plan view thereof; and,

FIG. 7 is bottom plan view thereof.

The broken lines in FIGS. 4 and 5 are included for the purpose of illustrating a portion of the nasal cannula body that forms no part of the claimed design.
